United States Patent

Des. 239,906
Patented May 18, 1976

239,906

LID FOR A WATER RESERVOIR TYPE COFFEE- MAKER OR SIMILAR ARTICLE

Max C. Hauenstein, Monroe, Conn., assignor to
General Electric Company

Filed Feb. 27, 1974, Ser. No. 446,521

Term of patent 14 years

Int. Cl. D7—02

U.S. Cl. D7—131

FIG. 1.

FIG. 2.

FIG. 3.

FIG. 4.

FIG. 5.

FIG. 1 is a top perspective view of a lid for a water reservoir type coffeemaker embodying my new design;

FIG. 2 is a top plan view thereof;

FIG. 3 is a front elevational view thereof;

FIG. 4 is a bottom plan view thereof; and

FIG. 5 is a side elevational view thereof.

I claim:

The ornamental design for a lid for a water reservoir type coffeemaker or similar article, as shown.
